ATT'Y.

UNITED STATES PATENT OFFICE.

ROBERT C. M. BOWLES, OF BROOKLINE, MASSACHUSETTS.

DESIGN FOR A STETHOSCOPIC INSTRUMENT.

SPECIFICATION forming part of Design No. 28,307, dated February 22, 1898.

Application filed December 27, 1897. Serial No. 663,770. Term of patent 14 years.

To all whom it may concern:

Be it known that I, ROBERT C. M. BOWLES, residing in Brookline, in the county of Norfolk and State of Massachusetts, have invented a new and original Design for Stethoscopic Instruments, of which the following description, in connection with the accompanying drawings, is a specification, like letters on the drawings representing like parts.

10 The design relates to a stethoscopic instrument; and it consists of a stethoscopic instrument distinguished by its peculiar shape, as will be hereinafter set forth and claimed.

Figure 1 is a top or plan view of a stethoscopic instrument embodying this design, and Fig. 2 a side elevation of the instrument shown in Fig. 1.

15 The leading and distinguishing feature of this design consists in a stethoscopic instru-

ment of the shape or configuration shown and 20 consists of a substantially thin body *a*, having extended from its back or upper surface a tube or pipe *a'*, which, arising from substantially the center of said body, extends toward and to near the rim of the same in a plane 25 approximately parallel to the front or lower surface thereof.

I claim—

20 The design for a stethoscopic instrument herein shown and described.

30 In testimony whereof I have signed my name to this specification in the presence of two subscribing witnesses.

ROBERT C. M. BOWLES.

Witnesses:

JAS. H. CHURCHILL,
J. MURPHY.
